UNITED STATES PATENT OFFICE.

ERNEST RICHARDSON, OF COLLEGE, PENNSYLVANIA.

REFRIGERATOR-LINING.

1,160,530.

Specification of Letters Patent.

Patented Nov. 16, 1915.

Application filed September 19, 1914. Serial No. 862,577.

To all whom it may concern:

Be it known that I, ERNEST RICHARDSON, a citizen of the United States, residing at College, in the county of Beaver and State 5 of Pennsylvania, have invented new and useful Improvements in Refrigerator-Linings, of which the following is a specification.

My invention relates to linings for refrigerators and its object is to provide a lining, preferably of the L-shaped type, composed of sections joined together in a novel manner whereby the process of manufacture is cheapened and the desired shape of 10 the linings preserved. It is difficult to make perfect enameled L-shaped linings which are made integral or which have portions or compartments thereof rigidly secured together before the enamel is burned on, owing to the liability of the lining to warp or 15 twist in the enameling furnace or during its cooling. I propose to make the horizontal projecting member of an L-shaped refrigerator lining separate from the vertical member and then connect the members together in a novel manner.

Referring to the accompanying sheet of drawings, Figure 1 is a perspective of a lining embodying my invention together with 20 the outline of an ice-box; Fig. 2, a front elevation of Fig. 1; Fig. 3, a perspective of one section of the lining; Fig. 4, a perspective of the other section of the lining; and Fig. 5, a detailed perspective view.

I prefer to make my refrigerator lining in two sections, or compartments, marked A and B. The section A is substantially equal in height to the combined height of the section B and the ice-box C shown in 25 40 dotted lines on Fig. 1 and in full lines on Fig. 2.

The section, or compartment, A has the vertical side walls 1 and 2, the vertical rear wall 3, the top 4, and the bottom 5, all preferably integral or rigidly secured together and enameled. The front of this elevation is left open and provided with flanges which may extend in either direction parallel with the back 3 or at right angles to the sides, 30 top, and bottom. The section A in the side 2 at or near the lower end thereof has a rectangular opening 6, there being a horizontal flange 7 extending outwardly at right angles to the side 2 along the upper edge of the 35 opening.

The section, or compartment, B has the

bottom 8 at the same level as the bottom 5 and having the same depth; the vertical rear wall 9 at the rear edge of the bottom 8 and in line with the wall 3; and the vertical side 10 parallel with the wall 2 and continued upwardly from the side of the bottom 8 farthest from the section A. The bottom 8 and the walls 9 and 10 are preferably integral or rigidly connected together 60 and enameled. The edges of the bottom 8 and the rear wall 9 are provided at their edges nearest the section A with the inturned flanges 10' and 11 which register with, and lie close to, the flanges 12 and 13, respectively, extending inwardly from the wall 3 and the bottom 5. The top of the wall 9 has the forwardly or inturned flange 14 at the same level as the flange 7. The top of the side 10 has the flange 15 at the same level as 70 the flanges 7 and 14. The forward edges of the bottom 8 and side 10 have flanges similar to those in the forward edges of the section A. The section B has preferably no top, front, or side next to the section B. The 75 flanges 7, 14, and 15 form horizontal supports for the bottom of the ice-box C and at the same time constitute effective means for stiffening the sections A and B.

16 is an opening in the upper portion of 80 the wall 2 for air to pass from the section A to the ice-box C. Cold air from the ice-box passes through the opening 6 to the bottom of the section A and thence up the latter to the opening 16.

The adjacent pairs of flanges 10' and 12, and 85 11 and 13 are covered by the L-shaped strip D of enameled metal having a U-shaped or channel-shaped cross-section, the edges of the flanges lying in the bottom of the U 90 or channel, while the sides of the latter lie next to the outer faces of the flanges. The strip D is secured in place by the nails 17 driven through holes in the strip, between the flanges of the sections A and B, and into 100 the substraction (not shown) on which the sections rest. The strip D improves the appearance of the lining by giving a good finish; it protects the edges of the flanges from blows and rust; and it aids in holding 105 the sections immovably together.

I claim;

1. In a refrigerator a lining, having two sections, one having in one side an opening, and an outwardly extending flange at the 110 upper edge of the opening, the other section lying adjacent to the first section and hav-

2
ing its upper edges at the same level as the said flange, in combination with an ice-box resting on the said flange and on the top of the second section.

5 2. In a refrigerator a lining, having two sections, one section having in one side near the lower end thereof an opening bordered by flanges in the plane of the opening, the other section being adjacent to the first section and having flanges registering with the first named flanges, and a U-shaped strip covering the edges and outer sides of the said flanges.

15 3. In a refrigerator a lining, having two sections, one section having in one side near the lower end thereof an opening bordered by flanges in the plane of the opening, the other section being adjacent to the first section and having flanges registering with the first named flanges, a U-shaped strip covering the edges and outer sides of the said

flanges, and fastenings for the strip extending through the angle of the strip and between the adjacent flanges.

4. In a refrigerator a lining, having two sections, one section having in one side an opening with walls thereof in the plane of the opening, the other section being adjacent to the first section and having flanges 25 registering with such walls and parallel therewith, and a U-shaped cover for the joint between the said flanges and the walls 30 registering therewith, one of the sides of the U-shaped cover overlapping the flanges and walls and parallel with the same. 35

Signed at Beaver Falls this 16th day of September, 1914.

ERNEST RICHARDSON.
